US0D1044185S

(12) **United States Design Patent** (10) **Patent No.:** **US D1,044,185 S**
Hall (45) **Date of Patent:** **** Sep. 24, 2024**

(54) **VACUUM ATTACHMENT FOR A POCKET HOLE JIG**

5,407,307 A 4/1995 Park
5,676,500 A 10/1997 Sommerfield
5,791,835 A 8/1998 Chiang et al.

FIG. 1 is perspective view of an embodiment of a vacuum attachment;

FIG. 2 is a side view thereof;

FIG. 3 is a side view thereof showing the side opposite that shown in FIG. 2;

FIG. 4 is a front view thereof;

FIG. 5 is a rear view thereof;

FIG. 6 is a top view thereof; and,

FIG. 7 is a bottom view thereof.

The broken lines illustrate environmental features that form no part of the claimed invention.

1 Claim, 6 Drawing Sheets
